RAILROAD SWITCH REFLECTORIZED SEMAPHORE

William A. Teasel, 251 Strathmoor, and Wallace A. Stanley, 24665 Waldon Road E., both of Birmingham, Mich.

Filed Mar. 5, 1971, Ser. No. 121,610

Term of patent 14 years

Int. Cl. D29—99

U.S. Cl. D72—1 G

FIG. 1 is a perspective view of a railroad switch reflectorized semaphore.

FIG. 2 is a perspective view of a second embodiment of our new design.

FIG. 3 is a perspective view of a third embodiment of our new design.

FIG. 4 is a top plan view of the first embodiment on a reduced scale.

FIG. 5 is a side elevational view thereof.

FIG. 6 is an elevational view thereof as seen from the corner.

FIG. 7 is a bottom plan view thereof.

FIG. 8 is a fragmentary view of the front surface of one of the reflector units on an enlarged scale.

FIG. 9 is a fragmentary view of the rear surface thereof.

FIG. 10 is a cross-sectional view taken on line 10—10 of FIG. 9.

The faceting on the reflector units is omitted in FIGS. 1, 2, 3, 5 and 7 for convenience of illustration.

We claim:

The ornamental design for a railroad switch reflectorized semaphore, as shown and described.
